UNITED STATES PATENT OFFICE.

ROLLIN H. TRUMBULL, OF CHICAGO, ILLINOIS.

INTERCHANGEABLE PANORAMIC CAMERA.

SPECIFICATION forming part of Letters Patent No. 691,020, dated January 14, 1902.

Application filed December 13, 1900. Serial No. 39,587. (No model.)

To all whom it may concern:

Be it known that I, ROLLIN H. TRUMBULL, a citizen of the United States of America, residing at Chicago, in the county of Cook and 5 State of Illinois, have invented certain new and useful Improvements in Interchangeable Panoramic Cameras, of which the following is a specification.

My invention relates to certain improvements in interchangeable panoramic cameras of the class in which means are provided for taking a panoramic view of the surroundings of the cameras and also means for using the camera in the ordinary way to photograph 15 the object in front of it in any given position.

The invention has particularly to do with certain novel devices applicable to cameras of this class, by reason of which the work of the camera is greatly improved and the difficulty of manipulating the same considerably lessened. The advantages attained by the various improvements will appear in connection with the description of said improvements, and the essential characteristics of the 25 improvements will be clearly defined in the claims.

In the drawings, Figure 1 is a perspective of a complete camera. Fig. 2 is a plan of the interior of the camera with the case removed. 30 Fig. 3 is a horizontal section in line 3 3 of Fig. 6. Fig. 4 is a broken horizontal section in line 4 4 of Fig. 5. Fig. 5 is a vertical section in line 5 5 of Fig. 4. Fig. 6 is a side elevation of the parts seen in Fig. 2, with certain 35 portions broken away, the view being in the direction indicated by the arrow 6 in said figure. Fig. 7 is a vertical section in line 7 7 of Fig. 3. Fig. 8 is a rear elevation of the inner box of the camera. Fig. 9 is a broken vertical section in line 9 9 of Fig. 3. Fig. 10 is a horizontal section in line 10 10 of Fig. 8, and Fig. 11 is a broken perspective of a swinging film-covering door.

Looking at Fig. 1, A is the cover or case of 45 the camera-box, supported upon legs a a' a'', at the top of which is a gear a³, fast to the legs and having an upwardly-projecting spindle a⁴, entering a tubular socket a⁵, furnishing a vertical pivot for the camera.

50 Looking now at Fig. 8, a pinion a⁶ is seen projecting from the lower portion of the camera-box, which is lettered A', said gear being

also shown in dotted lines in Fig. 3 as being fast upon a shaft a⁷, secured to a friction-roller a⁸, bearing upon the film B. Said film 55 is carried by a spool B' and is wound upon a spool B², passing from the spool B', first between a fixed plate b¹ and an adjustable swinging plate b², pivoted at b³, (see dotted lines in Fig. 6,) and preferably having at its 60 free end a roller b⁴. Between its ends two brackets b⁵, (see Fig. 6) secured, respectively, at the top and bottom of the case, are provided with adjusting-screws b⁶, bearing upon the swinging plate to tighten it upon the film. 65 This device furnishes a means for adjusting the tension upon the film to keep the exposed surface taut. From between these tension-plates the film passes around a roller b⁷, (see Fig. 3,) then across the back of the case and 70 around a roller b⁸, and then over an idler b⁹ to the friction-roller a⁸, from which it passes to the winding-spool B². The spindle of said spool is lettered B³ and extends through the top of the case, bearing upon 75 its outer end a gear c, which forms a part of a train of gears c' c² c³ c⁴, the last two being secured upon spindles c⁵ c⁶, provided with springs which may be wound up in the manner of ordinary clockwork, a full 80 description of which is thought unnecessary. These gears are supported in a framework C, supported by posts C', secured to the case A' and bearing elastic washers C², preferably of rubber, to take up any vibration of the clockwork. From the gears c³ c⁴ a second train of 85 gears rotates a regulating or governing spindle c⁷, (see Fig. 4,) said spindle bearing a friction and brake disk c⁸ and below the same a governing device c⁹, which may be of any 90 well-known form—as, for instance, an ordinary escapement, a fan, or a centrifugal brake—the function of said device being to limit the maximum speed of the spindle. The spindle a⁷ (see Fig. 3) of the friction-roller a⁸ 95 extends upward through the top of the case and has secured upon its outer end a pinion d, (see Fig. 2,) in mesh with a gear d', in mesh with a gear d² upon a spindle D. (See Fig. 4.) Upon this spindle is secured a split collar d³, 100 Fig. 5, the top of which is provided with a knurled head D', by means of which the split collar may be turned upon the spindle. Said collar has fast upon it a notched stop-disk d⁴,

having a notch d^5 , (see Fig. 4,) adapted to receive when turned to the proper position the bent end e of a stop-lever E , pivoted vertically at e' and provided with a second arm 5 having the upwardly-bent end e^2 , adapted to bear upon the brake-disk c^8 . A coiled spring e^3 tends to press the end e^2 against the brake-disk and does so whenever the end e drops into the notch d^5 . Upon the collar d^3 is an 10 outer collar d^7 , having sufficient frictional engagement therewith to be rotated thereby and at the same time easily movable upon the same to enable it to be set in any desired position. This outer collar bears a cam d^7 , having 15 a curved edge d^8 , adapted to crowd the end of the stop-lever from the notch d^5 , and shoulders $d^9 d^{10}$, adapted to bear, respectively, upon pins $d^b d^c$ in the notched disk to limit the angular movement of the cam upon said 20 disk. When this disk is turned over the notch, it completes the contour of the disk and prevents the end of the stop-lever from entering said notch. Upon the upper portion of the outer collar is a dial-disk d^e and above 25 the same an annular head d^f , by means of which the outer collar may be turned. When the cam is in the position seen in Fig. 4, exposing the notch, the dial-disk always has a position fixed relatively to the notched disk, 30 so that it affords means for determining at a glance the position of said notch.

Adjacent to the brake-disk c^8 is a spindle f , extending from the top of the case and bearing outside of the same a button F . Within 35 the case it carries a brake-arm f' , (see Fig. 4,) adapted to bear upon the brake-disk, and a crank-arm f^2 , to which is secured a cord f^3 , passing over a pulley f^4 , Fig. 7, and secured to a slide f^5 , perforated at f^6 to the size of 40 the lens or largest shutter-opening and guided vertically in guides $f^7 f^8$. By turning the button F to bring the brake-arm upon the brake-disk the motion of the gear is stopped, checking the movement of the film and the 45 rotation of the camera-box, and at the same time the slide f^5 is drawn upward, shutting off the light from the lens and protecting the portion of the film which happens to be exposed at that time. This enables the operation 50 of the camera to be temporarily checked in case an object which is not desired to photograph appears upon the scene, and the camera need not be started again until the scene is in proper condition. A pair of springs f^9 assist the downward movement of the slide. 55 In the rear portion of the box, Figs. 3 and 10, is a vertical post g , upon which is secured a swinging door G , Fig. 11, which may be swung across the box to cover the film, as seen in 60 Figs. 10 and 3, or may be swung along parallel with one of the partitions x , as seen in dotted lines in Fig. 3. The post g is provided with a flat spring-arm g' , perforated at g^2 , and pins g^3 are provided upon the bottom of 65 the case to enter the perforation and hold the arm in the desired positions. Upon the opposite side of the box is a similar post H , hav-

ing a similar arm h to swing around and engage the edge of the swinging door when the same is placed in front of the film. The door G 70 is vertically slotted at g^4 , and a slide g^5 is mounted in guides g^6 and moved horizontally by means of bell-crank levers $g^7 g^8$, pivoted to the slide at $g^9 g^{10}$ and to the door by means of pivots $g^b g^c$, extending through slots 75 $g^d g^e$ in the slide. The two bell-crank levers are connected by a bar g^f , guided in brackets $g^h g^i$, secured to the door. The slide affords means of adjusting the width of the slot, and consequently the extent of the exposure of 80 the film as it moves past the slot. Back of the film is pivoted a plate K upon a post k , extending through the top of the case and bearing an arm k' , connected to a spring k^2 , tending to draw the arm so as to crowd the 85 plate against the back of the film and hold the latter tightly against the slotted portion of the door.

The various portions of my invention are in certain respects independent of the exact 90 form or arrangement and may be used together or separately, as is thought desirable.

I claim as new and desire to secure by Letters Patent—

1. In a rotatable camera, the combination 95 with a rotating camera-box, of clockwork for rotating the same, supported by the box and separated therefrom by elastic washers to take up any vibration of the clockwork; substantially as described.

2. In a panoramic camera, a motor for rotating the camera-box and moving the film transversely to the lens through a predetermined distance, means for releasing said motor and means for locking the same automatically, of a device for arresting the movement of the motor and shutting off the light from the film intermediate said movement of the motor; substantially as described.

3. In a panoramic camera, the combination 110 with the lens, camera-box, mechanism for rotating the box and simultaneously moving the film transverse to the lens, and devices for setting said mechanism to rotate the box and move the film through a predetermined distance, and automatically stopping the movement thereof at the end of said time, of a hand-operated device and suitable connections therewith adapted to simultaneously arrest the movement of the box and film and 115 shut off the light therefrom, intermediate said predetermined movement thereof; substantially as described.

4. In a panoramic camera, the combination 125 with a rotating box and a motor for running the same, of a train of gears driven by the motor, a stop-lever tending to move into a position to stop the train, a notched stop-disk rotated by the motor and adapted to engage the stop-lever and hold it out of operative 130 position, except when the portion of the lever bearing upon the disk registers with the notch and an independently-movable device for covering the notch to prevent the end of

the lever from entering the same; substantially as described.

5. The combination with a camera having a device for supporting and moving a film, of a movable tension device adapted to bear upon the film and an adjusting device adapted to move the tension device toward the film; substantially as described.

6. The combination with a camera containing film supporting and moving devices, of a fixed guide and a pivoted guide between which the film passes and an adjusting device for crowding the pivoted guide toward the film; substantially as described.

15 7. In a camera having film supporting and moving devices, the combination with a fixed guide and pivoted guide having a roller upon its free end adapted to bear upon the film, of means for crowding the pivoted guide toward the film; substantially as described.

8. In a panoramic camera, the combination with a slotted film-cover between the lens and film, of a slide mounted alongside of said film-cover and guided to move over the slide, bell-crank levers pivoted to said slide and film-cover and a link connecting the ends of said bell-cranks adapted to move said slide over said slot; substantially as described.

9. In a panoramic camera, the combination with a slotted film-cover between the lens and the film, of a slide mounted alongside of said film-cover and guided to move over the slot and an operating device connected with both ends of said slide and adapted to move them simultaneously; substantially as described.

35 10. In a panoramic camera, the combination with devices for supporting and rotating the

camera and for supporting and simultaneously moving the film, of a film-cover slotted transversely of the film movement and arranged between the film and the lens and a device on the opposite side of the film adapted to press the same closely to the slotted portion of the film-cover; substantially as described.

40 11. The combination with a panoramic camera and with a slotted film-cover between the film and the lens, of a pivoted device for pressing the film toward the slotted portion of the cover, said pressing device being provided with a spring tending to crowd it toward said cover; substantially as described.

45 12. In a panoramic camera, the combination with the box, lens, and motor for rotating the box and moving the film transverse to the lens, a device for locking said motor, a setting device for unlocking the motor to permit the same to move the camera-box and film through a predetermined distance, of a curtain, a button, devices connecting said button with the motor and with the curtain adapted by the movement of said button to simultaneously arrest the movement of the motor and draw the curtain over the lens; substantially as described.

55 60 In witness whereof I have hereunto set my hand, at Chicago, in the county of Cook and State of Illinois, this 15th day of October, A. D. 1900.

ROLLIN H. TRUMBULL.
